UNITED STATES PATENT OFFICE.

SEBEUS C. MAINE, OF BOSTON, MASSACHUSETTS.

CRUTCH.

SPECIFICATION forming part of Letters Patent No. 254,348, dated February 28, 1882.

Application filed September 16, 1881. (No model.)

To all whom it may concern:

Be it known that I, SEBEUS C. MAINE, of Boston, in the county of Suffolk and State of Massachusetts, have invented certain new and useful Improvements in Crutches, of which the following is a full, clear, and exact description.

These improvements in crutches consist, first, of a ball-and-socket connection or joint between the cross-piece for the support of the person beneath the armpit and the staff; second, of a peculiar arrangement of the hand-rest upon the staff, which rest is capable of being adjusted and fixed as to its height at pleasure; third, of a cross-piece for the support of the person beneath the armpit, made of cork, of suitable shape, and confined within a shell, with its upper surface exposed and making a bearing for the person beneath the armpit, all substantially as hereinafter described.

In the accompanying plate of drawings, Figure 1 is a side elevation of a crutch broken away in its length, and at parts in vertical section. Fig. 2 is a side view, on an enlarged scale, at the foot portion of the crutch, with parts in vertical section. Fig. 3 is a vertical section, on an enlarged scale, of the crutch-support of the person beneath the armpit.

In the drawings, A represents the staff, split into two branches for a portion of its length; B, the foot, and C a cross-piece joining the upper ends of the two branches of the staff, all substantially as well known.

The cross-piece C carries a rest or support, D, for the person beneath the armpit. This rest or support D is of the ordinary shape in its length and width, and it is made of cork, placed within a shell or casing, E, shaped to surround it upon all its sides except its upper and bearing side, for the rest of the person under the armpit.

The cork F is secured in its shell or casing by screws *a*, which pass through the shell and screw into nut-blocks *b*, located within the thickness of the cork at suitable parts thereof.

The armpit-support D has a ball, G, attached to it, which enters into a socket, H, of the cross-piece C of the crutch, and is there confined against escape by a plate, *d*, of convex shape, which sets over said ball G, and is fastened to said cross-piece by screws *f* or other suitable fastening devices, and all so that said

support, by its ball G, can roll or rock in its socket H of said cross-piece without liability of escape therefrom.

The foot B of the crutch is provided with a foot piece or pad, K, made of india rubber or of any other suitable material, and of any suitable form or style. This foot-pad has a shoulder, *g*, which rests upon a shoulder, *h*, at the open end of the cylindrical thimble or sleeve L, having two or more longitudinal slots, *l*, each of which runs from the other and open end of the sleeve, and between the two ends of the sleeve each of said slots terminates in a slot, *m*, that runs transversely to the length, and has an inclination toward the said shouldered end, and extends partially around and about the sleeve. This sleeve fits by its open and slotted end the foot of the staff, and this foot has pins or studs *n*, suitably located for each to enter a sleeve-slot, *l*, and by forcing the sleeve on the staff to pass down the longitudinal slots *l*, and thence by turning the sleeve or staff to pass into the transverse portions *m* of the slots, all in connection with the abutment of the foot-pad K against the end *o* of the staff, and the described shouldered bearing of said pad within the sleeve securing an attachment of the foot-pad to the staff. A support or rest, D, of the crutch for the person beneath the armpit, made of cork, is especially advantageous, as it is a non-conductor of heat, is elastic and yielding, and is not an absorbent of the moisture or perspiration under the armpit. And, again, the attachment of a support for the person under the armpit to the staff by a ball-and-socket joint, as described, secures freedom of play thereto to accommodate it to the ever-changing movements of the person in walking with and resting upon the crutch, thereby relieving the muscles and other parts of the person of undue strains and other disagreeable and well-known injurious effects from the use of crutches.

An attachment of the foot-pad such as herein described enables the pad to be easily attached and detached for replacement when worn out, or for a change from a pad or foot of one kind or style to another.

M is a hand-rest, extending across the crutch between its two branches.

P is a screw-threaded pin, projecting at each

end of the hand-rest or handle, and having its screw-threads in each case running in opposite directions. These screw-threaded pins each enter a screw-threaded socket, *r*, and each 5 socket is part of separate and distinct sleeves *N N*, of suitable shape each to loosely fit and slide upon a branch of the staff *A* when not confined thereto. The turning of the handle in one direction draws the sleeves *N* toward 10 each other and binds them and the ends of the screw-pins against the opposite sides of the branches of the staff, and thus fixes the handle in position and against movement along the length of the branches of the staff. The turning 15 of the handle in the other direction moves the sleeves away from each other, and thus loosens their bind upon and also the bind of the screw-pins against the branches of the staff, leaving the handle then free to be adjusted as 20 to its height upon the staff, when, turning the handle in the reverse direction, it can be fixed in such adjusted position, as before described. This arrangement of the handle or hand-rest obviously enables it to be adjusted as to its 25 height on the staff, as may be desired to suit varying lengths of the arms of persons, and for other purposes.

The ball-and-socket attachment of the rest for the person under the armpit herein described obviously is not limited in its use to any special form or kind of such support.

Having thus described my invention, what I claim, and desire to secure by Letters Patent, is—

1. A crutch having the rest or support for 35 the person under the armpit attached to the staff with a single ball-and-socket joint, substantially as described, for the purpose specified.
2. A crutch having the rest or support for 40 the person under the armpit made of cork, secured in a suitable shell or casing, substantially as and for the purpose described.
3. The combination, with the branches of a crutch, of the hand-rest *M*, the pin *P*, passing 45 through the hand-rest, and screw-threaded at its ends, as set forth, and the sleeves *N*, having sockets receiving said screw-threaded ends of the pin, whereby by turning said hand-rest in one direction the sleeves will be drawn toward 50 each other, and thereby secured upon the branches of the crutch, substantially in the manner and for the purpose described.

In testimony whereof I have hereunto set my hand in the presence of two subscribing 55 witnesses.

SEBEUS C. MAINE.
